UNITED STATES PATENT OFFICE

JAMES BAXTER ROBERTSON, OF PATERSON, AND GEORGE ROBERTSON, OF RIDGEWOOD, NEW JERSEY, ASSIGNORS TO THE PARATEX CORPORATION, OF PATERSON, NEW JERSEY, A CORPORATION OF NEW JERSEY

NEEDLING MACHINE

Application filed December 31, 1927. Serial No. 243,799.

This invention relates to the manufacture of textiles such as rugs and particularly to needling machines for forcing fibers or other material which forms the nap of the rug or other textile product through the material which forms the base material of the rug.

In producing relatively inexpensive rugs having a nap of vegetable or animal fiber or similar material a layer or "bat" of fibrous material cut into short lengths is placed upon a long web of the base material. The web is then passed through a needling machine where the fibers are forced through the base material by needles having downwardly-extending barbs which pierce the base material. Stripper bars are provided directly above the layer of fibrous material that is being forced through the web in order to remove the fiber from the needles as they are withdrawn. These needles and the stripper bars are usually placed in alternate parallel rows transverse to the direction of movement of the backing material.

Because of the rapid reciprocating motion of the frame which carries the needles the whole machine is continuously and severally vibrated. The rapid succession of impacts of the stripping action also tends to set the stripper bars to vibrating. When small size rugs are made and the stripper bars are short their vibration is not serious but with the larger sizes of rugs where the stripper bars are much longer their vibration often becomes so severe that the bars move into the path of the needles breaking the needles and in some instances the stripper bars are broken.

One of the objects of the present invention is to provide a needling machine that will permit the manufacture of rugs of unusual width.

Another object of the present invention is to prevent the breaking of the needles or stripper bars of needling machines.

It is an important feature of the invention that supporting members for resisting the impact of the material during the needling action are positioned obliquely to the direction of movement of the material being needled.

Other important features and objects of the invention will be apparent from the accompanying description and drawings, in which

Figure 1 is a vertical sectional view of a needling machine embodying the present invention;

Figure 2 is a detailed view in section taken on the line 2-2 of Figure 1; and

Figure 3 is a plan view of the stripper frame positioned at right angles to that shown in Figure 2.

The present invention as shown, consists of a base 1 having a guideway 2 in which a needle frame 3 is designed to reciprocate. The needles 4 are carried by the frame 3 and are positioned closely together over the entire surface of the needle frame except in those portions of the frame which are directly over the stripper bar supports. The needle frame may be reciprocated by any suitable means such as the eccentric 5 driven from a gear 6. Stripper bars 8 are positioned above the web of rug-making material and in the embodiment shown extend the full width of the machine. These bars may be solid or of a light tubular construction and are secured at the ends in a stripper frame 9 by any suitable means such as the nuts 10 threaded onto the outer ends of the bars.

In the present invention the needling machine is constructed of unusual width to accommodate a very wide web of the burlap or other base forming material. For example, when a "nine by twelve" rug is to be made the burlap is ordinarily 120 inches in width and this is afterwards trimmed down to 108 inches. It would be necessary with the type of stripper frame used heretofore that the stripper bars should be somewhat over 120 inches in length and relatively small in diameter.

These stripper bars operate to remove any fiber clinging to the needles as they are withdrawn from the web of material forming the base for the rug.

The web of burlap forming the base is passed through the needling machine from the roller 12 shown in Figure 2 to the roller 13. The "bat" of fibrous material is carried

on the upper surface of the burlap and passes beneath the stripper bars 8 and over the longitudinally-arranged supporting members 15. In order to prevent excessive vibration 5 of the stripper bars 8 due to the vibration of the machine solid or tubular supports are provided for the stripper bars between their ends. It is necessary, however, that the supporting members should not interfere with 10 the needling operation or cause any portion of the rug to pass out of the machine without being needled. In order to overcome this difficulty and at the same time to furnish adequate support for the stripper bars, supporting 15 members 16 are provided which are positioned obliquely of the stripper bars and obliquely to the direction of movement of the rug-making material through the needling machine. It has been found that stripper 20 bars of the length necessary for producing a rug nine feet wide should be supported at several points and in the example cited four such supports are employed.

The needles in the needle frame which 25 would engage the supporting members, when moved downwardly, are omitted so that as shown in Figure 3, the first rows of needles 18 operate upon the entire width of the rug-making material except at those points directly over the supporting members. Each 30 succeeding row of needles has a corresponding space directly over the support for the stripper bars but in every instance the gap between the needles is displaced from the corresponding gap in the preceding and succeeding 35 row of needles. Thus, as the web of material moves in the direction of the arrow shown in Figure 3, the portion of the material which was previously covered by the support 40 12 and which was not operated on by the previous row of needles is subjected to the operation of the succeeding rows of needles so that as the material passes out of the machine every portion of the rug has been subjected 45 to the necessary needling operation. In this way it is possible to support the stripper bars at a sufficient number of points to prevent their breaking the needles or otherwise interfering with the operation of the 50 machine without leaving a strip of material which has not been subjected to the necessary amount of needling to furnish a substantially uniform product.

The needles, as shown on the drawing, 55 should be staggered along the direction of travel of the web and avoid straight rows parallel to that direction so that the web will be uniformly needled and no lanes of substantial width will be left on the web which 60 have not been subjected to the action of at least some needle.

What is claimed as new is:

1. In a needling machine for making rugs or similar textile products, a plurality of 65 needles for forcing fiber through a web of

material forming a base for the rug, stripper bars for removing fibers from the needles of said machine as they are withdrawn from the web, and a support for said stripper bars between the ends of said bars and positioned obliquely to said stripper bars. 70

2. In a needling machine for making rugs or similar textile products, means for moving a web of the rug-making material through the machine, a plurality of needles for forcing fiber through said web, stripper 75 bars for removing fiber from said needles as they are withdrawn from the web and a support for said stripper bars between their ends and positioned obliquely to the direction of movement of said web through said machine. 80

3. In a needling machine for making rugs, or similar textile products, means for moving a web of the rug-making material 85 through the machine, a plurality of needles for forcing fiber through said web, stripper bars for removing fiber from said needles as they are withdrawn from the web and a plurality of supports for said stripper bars between their ends and positioned at an angle 90 to both said stripper rods and the direction of movement of said web through said machine. 95

4. In a needling machine for making rugs or similar textile products, a plurality of needles positioned in parallel rows for forcing fiber through a web of material forming a base for the rug, and a stripper bar frame comprising a plurality of stripper bars parallel to said rows of needles and supporting members for said stripper bars positioned at 100 an oblique angle to said stripper bars. 105

5. A stripper bar frame for a needling machine comprising parallel stripper bars extending transversely of the direction of movement of the web of material over which said frame is adapted to be mounted and supports for said bars between the ends thereof and positioned at an oblique angle to said stripper bars. 110

6. In a needling machine for making rugs or similar textile products, a plurality of needles positioned so as to avoid straight rows in a direction parallel to the direction of movement of the web of material, and a stripper frame serving to remove fibers from the needles as they are withdrawn from the web, and including members serving to reinforce said frame extending between said needles in a direction oblique to the direction of travel of the material. 115

7. In a needling machine for making rugs or similar textile products, a plurality of needles positioned so as to avoid straight rows in a direction parallel to the direction of movement of the web of material, and a stripper frame serving to remove fibers from the needles as they are withdrawn from the web, and including stripper bars transverse to the direction of travel of the material and 120 125 130

members serving to reinforce said frame extending between said needles in a direction oblique to the direction of travel of the material.

8. In a needling machine for making rugs or similar textile products, a plurality of needles for forcing fiber through a web of material and a stripper bar frame having bars which serve to remove fibers from needles as they are withdrawn from the web, said frame including relatively short bars serving to bear a substantial part of the pressure of the web against said frame and extending between said needles in a direction oblique to the direction of travel of the material.

9. In a needling machine the combination as defined in claim 6, in which the stripper bar frame also includes stripper bars transverse to the direction of travel and arranged so as to be supported between their ends by the relatively short and obliquely positioned bars.

Signed at Paterson, N. J., this 15th day of December 1927.
